ALAN WRIGHT, OF LONDON, ENGLAND.

ELECTRICALLY-OPERATED ACTUATING DEVICE.

Application filed March 21, 1928, Serial No. 263,462, and in Great Britain February 24, 1927.

This invention relates to electrically operated mechanism for imparting intermittent motion to switches, valves, and the like, and it has for its object the provision of a mechanism that is of simple construction, of robust character, and is cheap to produce. A further object of this invention is to obtain a positive action in two directions so as to avoid the use of springs, counterweights and like devices, to effect the return movement. Another object of this invention is to economize in current consumption. A further object of the invention is to give an increased starting torque, and a still further object is to enable a greater torque to be produced in one direction than in the other.

I attain these ends by a construction which comprises essentially a field magnet, an armature coacting with said magnet the one having rotational movement relative to the other, stops to define and limit the movement of the rotational element, a tapped coil on one of said elements, a commutator arranged to move in unison with the rotating element and adapted to control the circuits through the tapped coil and the coil of the field magnet if same is of the electromagnetic type, brushes which coact with said commutator, electric couplings between the commutator and the coils of the armature and the magnet if so fitted and means for closing the electric circuit through the commutator and its brushes.

In the accompanying drawing which forms part of this specification Figures 1-9 are diagrammatic views showing various alternative forms of construction based on well-known electrical combinations of magnets and armatures, and Figures 10, 11, and 12, are views in front elevation, rear elevation and side elevation respectively, of the form of the invention shown in diagram Figure 9 carried into practice. Figures 1-9 show the following constructional forms:—Figure 1 a fixed electro field magnet with a continuously wound coil and a rotating armature having a tapped coil. Figure 2, a fixed permanent field magnet and a rotating armature having a tapped coil. Figure 3, a fixed electro field magnet having a tapped coil and a rotating armature having a continuously wound coil. Figure 4, a fixed electro field magnet with a tapped coil and a rotating permanently magnetic armature. Figure 5, a fixed armature having tapped coil and a rotating electro field magnet with a continuously wound coil.

Figure 6, a fixed armature with tapped coil and a rocking permanent field magnet. Figure 7, a fixed permanent magnetic armature and a rocking electro field magnet with a tapped coil. Figure 8, a fixed armature with a continuously wound coil and a rocking electro field magnet with tapped coil. Figure 9 is a modification of the type shown in Figure 1 in which the armature is provided with an interpole on which the tapped coil is wound.

Throughout these views 1 designates the field magnet, 2 the armature, 3 the tapped coil, 4 and 5 the segments of the commutator, 6 and 7 the brushes which coact with said segments, 8 and 9 the couplings between the segments of the commutator and the ends of the tapped coil 3, 10 the coupling between the tapping of the coil 3 and one end of the coil 22 of the electro field magnet when such is employed, 11 the coupling between the other end of said coil and the main supply 12, 13 the electric couplings between the brushes 6 and 7 and the main 12, and 14 the switch between said couplings and the main 12. The segments of the commutator and the brushes are so arranged that they are not simultaneously in contact when the armature is at rest and are only momentarily in contact when the segments move from one position to the other.

It will be seen that it is immaterial whether the field magnet is fixed and the armature rotates as shown in Figures 1, 2, 3, 4, and 9, or whether the armature is fixed and the field magnet rotates as shown in Figures 5, 6, 7, and 8, so long as the commutator is arranged to move with the rotating element, and it is also immaterial whether the tapped coil is mounted on the armature as shown in Figures 1, 2, 5, 6, and 9, or on the magnet as shown in Figures 3, 4, 5, 7, and 8.

The coil 3 in all cases is tapped substantially at the centre of its length but this is not obligatory so long as each part of it is sufficient to energize the element on which it is mounted.

The two ends of the tapped coil 3 are in electric couple with the two segments 4 and 5 of the commutator and the tapping of said coil is in circuit with the main 12 either through the coil on the element on which the tapped coil is not mounted as shown in Figures 1, 3, 5, 8, 9, and 10, or direct as shown in Figures 2, 4, 6 and 7. When the tapped coil 3 is mounted on the electromagnet and the armature has a continuous wound coil one

end of the armature coil is coupled to the segment 4 of the commutator and the other end to the tapping of the coil 3, but when the armature is of the permanently magnetic type 5 the ends of the tapped coil on the electromagnet are coupled to the two segments 4 and 5 of the commutator.

Two stops are provided to limit the movement of the rotating element the positions 10 of said stops being such as will bring the rotating element to rest with the poles of the armature in juxtaposition to the entrant curves of the pole pieces of the magnet. It will be understood that the motion of the 15 rotating element is only through a predetermined arc so that the movement is in effect a rocking one. In the construction shown in Figures 10, 11, and 12, the stops are formed by the ends of a curved slot 15 in the frame 20 16 carrying the field magnet in which a pin 17 carried by the armature moves.

In operation, assuming the parts to be in the positions shown in Figures 1-8, if the 25 switch is thrown over to complete the circuit through the brush and segment of the commutator at the time in contact with one another, current will flow through one end of the tapped coil thereby energizing the rocking element and setting it in motion, the direction of rotation depending on which end 30 of the tapped coil the current enters. The effect in all cases is to bring the poles of one of the elements into magnetic opposition to the poles of the other element which will 35 cause the rotating element to rock until it comes into contact with the other stop and at the same time the electric circuit in the relative half of the tapped coil is interrupted by one of the segments of the commutator moving 40 out of contact with its co-operating brush and by the same movement the other segment of the commutator and its brush are brought into contact with one another thus resetting the device for the reverse operation. 45 This movement also brings the pole pieces of the armature and field magnet into such relative positions that when the switch is moved over to the opposite contact, the electrical current is then caused to flow through 50 the opposite half of the tapped coil from the opposite end, thus reversing the polarity of the magnetic field set up by the tapped coil; the magnetic polarity of the field set up by the continuous, i. e. untapped coil, being unchanged.

It will therefore be seen that no springs, weights or the like are required to move the rocking element in either direction.

It will be understood that the motion of the 60 rocking element is taken either directly from said element or from the shaft 18 which carries it. If the device is intended to operate an electric switch same can be conveniently embodied with the device as shown in Figures 65 10 and 12 in which the switch comprises two

fixed wipers 19 and 20 insulated from one another and a contact plate 21 mounted on the combined armature and commutator and adapted to couple said wipers.

The starting torque and therefore the rapidity of the operation of the type of device shown in Figures 1, 3 and 5 may be increased by mounting an interpole 23 on the element carrying the tapped coil which operates to render the magnetic field more unstable. Referring to Figure 1, as an example, the current passing through one path in the tapped coil 3 energizes the armature and determines the magnetic polarity of the two poles *a*, *b*, and the polarity of the interpole 23 is the same as that of the pole *b*. The resultant effect of the interpole 23 and the pole *b* is that of a single pole located somewhere between these poles. This resultant effect is greater than that of pole *b* without the interpole 23, and results in a higher starting torque and an increased rapidity of action. To still further increase the starting torque the axis of oscillation of the rocking element is arranged eccentrically in relation to the centre of curvature of the poles of the other part so as to provide an "air gap" of a varying radial depth as shown in Figure 9.

When it is desired to obtain a greater torque in one direction than in the other the one part of the tapped coil is wound with a conductor having a different specific resistance from the coil used in winding the other half, or the same result may be effected by winding both halves of the tapped coil with the conductor having the same specific resistance throughout and inserting an independent external resistance in one or other of the alternative circuits at any convenient point between the operating switch and one or other ends of the tapped coil.

The segments of the commutator and the brushes are preferably arranged in the well-known manner to form an automatic "blow out" for quenching any arc that may be formed between the brushes and the commutator.

What I claim is:—

1. An electro-magnetic device comprising a field magnet and an armature coacting therewith one having rotational movement relative to the other, stops to define and limit the movement of the rotating element, a tapped coil on one of said elements, a commutator rotating in unison with the rotating element and adapted to control the circuit through the tapped coil, and brushes coacting with said commutator, so as to open and close said electric circuit.

2. An electro-magnetic device comprising a field magnet and an armature coacting therewith one having rotational movement relative to the other, stops to define and limit the movement of the rotating element, a tapped coil on one of said elements, means

for increasing the starting torque of the rotating element, a commutator arranged to rotate in unison with the rotating element and adapted to control the circuit through 5 the tapped coil, and brushes coacting with said commutator, so as to open and close said electric circuit.

3. An electro-magnetic device comprising a field magnet and an armature coacting therewith one having rotational movement relative to the other, stops to define and limit the movement of the rotating element, a tapped coil on one of said elements, a commutator arranged to rotate in unison with the 10 rotating element and adapted to control the circuits through the tapped coil, brushes coacting with said commutator, means for closing the electric circuits through the brushes and commutator, and means for increasing 15 the starting torque of the rotating element.

4. An electro-magnetic device comprising a field magnet and an armature coacting therewith one having rotational movement relative to the other, stops to define and limit 20 the movement of the rotating element, a

tapped coil on one of said elements, a commutator arranged to rotate in unison with the rotating element and adapted to control the circuits through the tapped coil, brushes coacting with said commutator, means for closing the electric circuits through the brushes and commutator, and means for giving the 30 rotating element an increased torque in one direction of its movement.

5. An electro-magnetic device comprising a field magnet and an armature coacting therewith one having rotational movement relative to the other, stops to define and limit the movement of the rotating element, a tapped coil on one of said elements, an inter- 35 pole carried by the element having the tapped coil, a commutator arranged to rotate in unison with the rotating element and adapted to control the circuits through the tapped coil, brushes coacting with said commutator, 40 means for closing the electric circuits through the brushes and commutator, means for increasing the torque of the rotating element in both directions of its movement.

ALAN WRIGHT.
